UNITED STATES PATENT OFFICE.

CARROLL BURTON, OF JOHNSTOWN, PENNSYLVANIA.

SWITCH-OPERATING MECHANISM.

1,125,957.

Specification of Letters Patent. Patented Jan. 26, 1915.

Application filed September 25, 1914. Serial No. 863,521.

To all whom it may concern:

Be it known that I, CARROLL BURTON, a citizen of the United States, and resident of Johnstown, in the county of Cambria and State of Pennsylvania, have invented certain new and useful Improvements in Switch-Operating Mechanisms, of which the following is a specification.

My invention relates to the construction of the tongue operating mechanism of switches, and while not restricted to such use, more particularly relates to the tongue operating mechanism of switches used as part of the equipment of street railways.

One object of my invention is to provide a switch operating mechanism of improved construction and having novel means whereby the switch tongue is moved into and held in switching position on the switch body.

Another object of my invention is to provide a switch operating mechanism having novel means for connecting the switch tongue and tongue holding mechanism whereby the swinging movements of the tongue in the recess of the switch body are facilitated.

A further object of the invention is to provide a switch operating mechanism of novel construction and adapted for use in moving and holding the switch tongue against either or both sides of the tongue recess within the switch body, as in a double throw switch, and in moving and holding the switch tongue against one side only of the tongue recess, as in a single throw switch.

A still further object of my invention is to provide a switch operating mechanism having the novel construction and arrangement of parts more fully described hereinafter and specifically covered in the appended claims.

Referring now to the drawings forming part of this specification, Figure 1 is a plan showing a switch operating mechanism constructed and arranged and applied for use on a switch structure in accordance with my invention. Fig. 2 is a transverse sectional elevation of the mechanism shown in Fig. 1, the section being taken on the line II-II of Fig. 1. Fig. 3 is an irregular section, taken on the line III-III of Fig. 1. Fig. 4 is a plan showing the manner of adjusting the spring links and the reach rod to transform the switch into a single throw switch in which the tongue is always held

against one side of the tongue recess. Fig. 5 is a plan, and Fig. 6 is a side elevation showing a modified, and the preferred, construction of the notched ends of the spring links forming part of my improved switch operating mechanism.

In the accompanying drawings, the numeral 2 designates the switch body of a tongue switch of a type adapted for use on street railways. The switch body is provided in its upper face with a longitudinal recess 3 in which the switch tongue 4 is pivotally mounted or positioned. The tongue 4 is pivoted at its heel on one end, in the recess 3, and the switch point on the opposite end of the tongue is arranged to swing sidewise from one side to the other of the recess 3 against the sides 5 and 6 of the recess 3.

The switch operating mechanism forming my invention, being adapted for use with any of the numerous known switch constructions, the switch is not fully illustrated or described in detail.

Secured on one side of the switch body 2 by means of the bolts 7, 7, is a rectangular hollow metal box or casing 8, having an open top side which is normally closed by a removable lid or cover plate 9. The casing 8 is provided, on the inner surface of its end and side walls, with projecting ribs or flanges 10 which engage with and support the cover plate 9, as will readily be seen by reference to Figs. 1 and 2. (In Fig. 1 the casing is shown with the lid or cover plate removed, for the sake of clearness.)

Projecting downwardly from the lower surface of the switch tongue 4, within the recess 11, to a point below the bottom of the recess 3 in the switch body 2, is an integral lug 12 having a transverse opening therein in which one end of the adjustable reach rod 13 is fastened by a nut 14 and lock nut 15. The opposite end of the rod 13 is upset or enlarged in diameter and the thimble or sleeve 16 positioned on the reduced portion of the rod 13 forms a separator which serves to hold the rod 13 rigidly in position on the lug 12 when the nuts 14 and 15 are screwed tightly in place. The length of the thimble or sleeve 16 may be varied to suit the dimensions of various switches to which my improved switch operating mechanism is applicable and in changing the switch to a single or double throw switch.

The enlarged or upset end of the reach rod

13 is provided with an internally threaded axial opening in which the screw threaded end of the rod extension 17 is secured so as to be adjustable to vary the overall length 5 of the rod and rod extension. The nut 18 and lock nut 19 on the screw threaded end of the rod extension 17 serve to hold the rod extension in adjusted position on the reach rod 13. The outer end of the rod extension 10 17 also is enlarged and the enlargement 20 has a circumferential groove 21 therein, with ends 22 and 23 defining the length of the groove. It is to be noted that the groove 21 is of a length which permits of a free or 15 relative sliding movement of the notched ends of the link sections 26 in the groove 21, this construction forming an important part of my invention. One end of the enlargement 20 is made polygonal in cross section, 20 (hexagonal, as shown), so that a wrench may be employed in adjusting the rod extension 17 on the rod 13 to vary the overall length of the switch rod.

On the inner surface of each end of the 25 box or casing 8 is a projection 24 having a depression 24^a therein and pivotally secured in each of these depressions is the hemispherical outer end of a sectional spring link 30 by which the switch tongue 4 is yieldingly held against either of the opposite sides 5 and 6 of the recess 3, depending upon the position into which the switch tongue is placed or moved and the manner in which the switch operating mechanism is adjusted.

35 Each spring link is made in two sections 25 and 26, and each section is provided with a flange 27 against which one end of a helical compression spring 28 engages when the spring links are assembled in operative position. An annular sleeve or thimble 29 extends lengthwise within the springs 28 and the adjoining or abutting cylindrical ends of the sections 25 and 26 of each spring link are movably seated within the sleeve 29. The 40 cylindrical ends between the flanges 27 are of a length which, when the springs 28 are compressed, permits of a relative approach or movement of the sections 25 and 26 and decreases the overall length of the spring links, 45 as is done in shifting the position of the switch tongue 4 in the recess 3 in the operation of the switch. The inner ends or the ends of the sections 26 of the spring links which engage the ends 22 and 23 of the 50 groove 21 in the enlarged end 20 of the rod extension 17 are notched, the notches having surfaces which embrace or encircle the surface of the circumferential groove in the enlargement 20. The notches in the one end 55 of the link section 26 may be made of such a depth so that the surfaces of the notches will bear against the bottom surface of the groove 21, in the manner shown in Fig. 1 but preferably the ends 26^a of the sections 60 are curved and made of a length by which

the abutting ends of the opposite link sections 26 are in engagement as shown in Fig. 4.

With the construction of Fig. 4 the spring links, when they reach the dead point or a 70 position in which their axial centers are in alinement with a line extending through the recesses 24^a, the surfaces of the notches will not be in engagement with the grooved portion 21 of the rod extension 17, encircled by 75 the notched ends of the links.

As has been stated, my improved switch tongue operating mechanism is applicable for use on single throw switches like that shown in Fig. 4, as well as double throw 80 switches constructed as shown in Fig. 1. By double throw switch is meant a switch in which the tongue is yieldingly held by the spring links against each side of the recess for the tongue in the switch body. By single throw switch is meant a switch in which the tongue is yieldingly held against only one of the two sides of the tongue recess, to which position it automatically returns when not held out of such position by a 85 switch iron or by the wheel flange of a car 90 passing over the switch.

When arranged as shown in Fig. 4, which is done by adjusting the reach rod extension 17 on the switch rod 13, and in some cases by lengthening or shortening the sleeve 16 on the reduced portion of the rod 13, the switch tongue 4 swings in the recess 3 as before, but in this arrangement the reach rod is adjusted so that the abutting ends 26 of the 95 spring links are not moved beyond the dead point or a point on a line extended through the pivotal centers of the pivoted ends of the sections 25 of the spring links. In this way the switch tongue 4 will always move into engagement and be held in contact with the same one side of the recess 3 in the switch body 2. The tongue operating mechanism is adapted for use on either a right or left hand single throw switch by adjustment of the reach rod 13.

Ordinarily the switch tongue 4 is shifted in the slot 3 of the switch body by a "switch iron", although the tongue may be connected to and actuated by a suitable lever mechanism, of any approved construction. In such case the operating lever may be connected to the connecting rod extension 17 or be directly connected to the switch 105 tongue.

In the operation of switches equipped with my improved switch operating mechanism and adjusted to hold the switch tongue against each of the opposite sides of the recess 3, as shown in Fig. 1, the switch tongue 4 is moved manually, preferably with a switch iron, from one side to the other of the recess in the switch body. With the tongue positioned as shown in the drawings 115 the tongue 4 is adapted to be moved from 120 the one side to the other by the action of the 125 switch iron.

right to left in Figs. 1 and 2. When the switch tongue 4 is moved from the position shown to a position at the opposite side of the recess 3, the reach rod 13 is moved from 5 right to left also, and at the beginning of its movement the springs 28 on the spring links are compressed until the spring links, which when in holding position extend lengthwise in a vertical plane at an angle to 10 a line through the pivoted outer ends of the spring links, are in axial alinement. When the position of the switch tongue 4 is shifted from one side to the other of the recess 3 the spring links, as they swing, are gradually shortened in length until they reach 15 a central position in their swinging movement. When in this central position their axial centers are in alinement and coincident with a line extending in a vertical 20 plane through the recesses 24^a in the projections 24 on the inner surfaces of the ends of the casing or box 8. Upon continuing the movement of the switch tongue 4 the notched ends of the spring links in engagement with the groove 21 will be moved beyond the dead point, which is on a line extending through the recesses in the projections 24. When this occurs the springs 28 25 act to extend or lengthen the spring lever sections 26 and cause the notched ends in engagement with the groove 21 in the reach rod to slide in the groove until in engagement with the opposite end of the groove. The springs 28 will then exert sufficient 30 force to move the switch rod and switch tongue 4 through the balance of the swinging movement of the tongue, and the sliding movement of the notched ends of the sections 26 in the groove 21 will effectually 35 prevent the spring lever sticking or binding on the reach rod when on the dead point, with the tongue in a central position or position midway in the swinging movement of the tongue. The tongue 4 then engages the 40 left hand side 6 of the recess 3, and the springs 28 will be in the relative angular position shown in dotted lines in Fig. 1 and will exert a force which yieldingly holds the 45 switch tongue in its shifted position. When it is desired to again shift the position of the switch tongue, the above described operations are repeated. In this case the rod 17 and spring links will be moved from left 50 to right, in such movement the spring links being moved from the dotted position shown in Fig. 1 until again in the position shown by full lines in Fig. 1, and when in this position, yieldingly holding the switch tongue against the side 5 of the recess 3. 55

60 In the operation of a single throw switch equipped with my improved mechanism, the switch tongue 4 is moved in the recess 3 in the same manner as has been described. In this arrangement of the mechanism the swinging movement of the tongue does not

move the spring links sufficiently to bring the notched ends of the lever sections 26 beyond the dead point or a point on a line extending through the pivotal connections of the spring link sections 25 with the ends 70 of the box 8, so that when released the tongue 4 will return to the side of the recess 3 from which it is moved.

The advantages of my invention will be apparent to those skilled in the art. The 75 apparatus is simple, is easily and cheaply constructed, and is readily kept in repair. By the use of my improved spring switch box, the tongue of the switch is yieldingly held in each of its two operative positions 80 by the spring links forming part of my improved spring switch box, and the movement of the switch tongue is assisted and furthered by the action of the spring links in the tongue shifting operations. 85

By a simple adjustment of the parts of the switch tongue operating mechanism the switch to which it is applied for use is transformed from a double throw into either a right or left hand single throw switch, 90 or vice versa.

Modifications in the construction and arrangement of the parts may be made without departing from my invention as defined in the appended claims.

I claim:—

1. In a switch, a pivoted tongue, a spring link for positioning the switch tongue on the switch, and a reach rod operatively connecting the spring link with the switch 100 tongue, said spring link being movable with and relatively to said reach rod.

2. In a switch, a pivoted tongue, a spring link for positioning the switch tongue on the switch, a reach rod operatively connecting 105 the spring link with the switch tongue, said spring link being movable with and relatively to said reach rod, and stops on said reach rod to limit the movement of the spring link on the reach rod. 110

3. In a switch, a pivoted tongue, a spring link for positioning the switch tongue on the switch, and a lengthwise adjustable reach rod operatively connecting the spring 115 link with the switch rod, said spring link being movable with and relatively to said reach rod.

4. In a switch, a pivoted tongue, a spring link for positioning the switch tongue on the switch, a reach rod operatively connecting 120 the spring link with the switch tongue, said spring link having a recessed end embracing said reach rod and being movable with and relatively to said reach rod.

5. In a switch, a pivoted tongue having a 125 reach rod secured thereto, a box having oppositely extending swinging spring links pivotally mounted therein, said links having forked ends arranged to move with and relatively to the reach rod in operating the switch. 130

6. In a switch, a pivoted tongue having a reach rod secured thereto, a box having oppositely extending swinging spring links pivotally mounted therein, said links having forked ends arranged to move with and relatively to the reach rod, and means on the reach rod engaged by said forked ends of the spring links to limit the movement of said links on the rod and yieldingly hold the switch tongue in operative position.

7. In a switch, a pivoted tongue having a reach rod secured thereto, a box having oppositely extending swinging spring links pivotally mounted therein, said links having forked ends arranged to move with and relatively to the reach rod, means on the forked ends of said spring links to hold the links out of contact with the reach rod in the relative movement thereof, and means on the switch rod to limit the relative movement of the spring links on the reach rod.

8. In a switch, a pivoted tongue having a reach rod secured thereto, and a box having oppositely extending swinging spring links pivotally mounted therein, said reach rod having an enlarged circumferentially grooved end and one end of said spring links being forked, with the forked ends thereof arranged to encircle the reach rod and move in said groove in moving and yieldingly holding the switch tongue connected to the reach rod in operative position.

9. In a switch, a pivoted tongue having a reach rod secured thereto, a box having oppositely extending swinging spring links pivotally mounted therein, said reach rod having an enlarged circumferentially grooved end and one end of said spring links being forked, with the forked ends thereof arranged to encircle the reach rod and move in said groove in moving and yieldingly holding the switch tongue connected to the reach rod in operative position, the forked ends of said links encircling the grooved enlargement projecting into holding engagement with each other to prevent contact of the bottom of said groove with the forked ends of said levers.

10. In a switch, a pivoted tongue having a reach rod secured thereto, a box having a swinging spring link pivotally mounted therein, said spring link having one end arranged to engage with and move on the reach rod, and stops on the switch rod engaged by said end of the spring link for limiting the movement of the spring link on the reach rod and to move and yieldingly hold the switch tongue in operative position.

11. In a switch, a pivoted tongue having a lengthwise adjustable reach rod secured

thereto, a box having a swinging spring link pivotally mounted therein, said link having a forked end arranged to engage with and move on the switch rod, and stops on the reach rod engaged by said end of the spring link to limit the movement of said link and yieldingly hold the switch tongue in operative position.

12. In a switch, a pivoted tongue having a reach rod secured thereto, and a box having a spring link pivotally mounted therein, said reach rod having an enlarged circumferentially grooved end, and one end of said spring link being forked and arranged to embrace the reach rod and to move in said groove in moving and yieldingly holding the switch tongue connected to the reach rod in each of a plurality of operative positions.

13. In a switch, a pivoted tongue having a reach rod secured thereto, a box having a swinging spring link pivotally mounted therein, said spring link comprising relatively movable flanged sections, a sleeve in which the adjacent ends of the sections are telescoped and a helical spring on the sleeve with its ends in engagement with the flanges on said link sections, said spring link having one end arranged to move on the reach rod, and stops on the reach rod engaged by said end of the spring link to limit the movement thereof on the switch rod and yieldingly hold the switch tongue in operative position.

14. In a switch, a pivoted tongue having a reach rod secured thereto, a box having oppositely extending swinging spring links pivotally mounted therein, said spring links comprising relatively movable flanged sections, a sleeve in which the adjacent ends of the sections are telescoped and a helical spring on the sleeve with its ends in engagement with the flanges on said link sections, said spring links having forked adjoining ends arranged to move on the reach rod, and stops on the reach rod engaged by said forked ends of the spring links to limit the movement thereof on the switch rod and yieldingly hold the switch tongue in operative position and the forked ends extending into holding engagement with each other to prevent contact between the forked ends of the spring links and the bottom of the groove in the enlarged end of the reach rod.

In testimony whereof, I have hereunto set my hand.

CARROLL BURTON.
